UNITED STATES PATENT OFFICE.

JEFFERSON B. HAYDEN, OF SAN ANGELO, TEXAS.

COTTER-PIN PULLER.

1,202,836.

Specification of Letters Patent. Patented Oct. 31, 1916.

Application filed October 23, 1915. Serial No. 58,463.

To all whom it may concern:

Be it known that I, JEFFERSON B. HAYDEN, a citizen of the United States, residing at San Angelo, in the county of Tom Green 5 and State of Texas, have invented certain new and useful Improvements in Cotter-Pin Pullers, of which the following is a specification.

This invention relates to tools and more 10 particularly to cross handled tools having two operating or engaging jaws.

The principal object of this invention is to provide a device of this character that will be used principally to pull cotter pins 15 that are secured in shafts, fly wheels or any other of the numerous devices in which they are employed.

It is well known that wire pliers and pincers have been used to pull cotter pins, also 20 claw hammers, and numerous makeshifts such as driving a nail through the cotter pin head have been employed but all of these methods have proved unsatisfactory in that they bend and twist the pin, and in many 25 parts of machines in which cotter pins are used these makeshifts can not be employed for lack of space.

Another object of this invention is to provide a device for pulling cotter pins by one 30 operation without bending or twisting or damaging them, and which will permit of being worked in machinery where the parts are difficult of access or the space restricted or limited.

Other objects such as simplicity, cheapness in manufacture, durability and the general improvement of the art will be more 35 fully brought out in the following specification and illustrated in the accompanying 40 drawings, in which:

Figure 1 is a side view of my device open, Fig. 2 is a similar view closed, Fig. 3 is a top plan view of Fig. 1, and Fig. 4 is a bottom plan view of Fig. 1.

As shown in the drawings, the device 45 comprises two portions 1 and 2, having operating handles 3 and 4 flattened at 5 and 6, respectively, to form hand grips.

The portion 1 is enlarged at 7 and bent upwardly and forward forming an engaging 50 jaw 8. This jaw 8 is split at 9 forming portions 10 and 11 and has serrated portions 12. The portion 2 is flattened at 13 and has its end bent upwardly forming a jaw 14 terminating in a point 15. The jaw 14 is 55 adapted to be inserted between the portions 10 and 11 of the jaw 8 and pivotally held therebetween by pivot 16 passing through apertures 17 and 18.

The operation of the device is as follows: 60 The point 15 of the jaw 14 is passed through the eye of the cotter pin and the serrations 12 of the jaw 8 brought into engagement with the body having the cotter pin therein, and by pressing the hand grips or portions 65 5 and 6 together the point 15 being in the eye of the cotter pin will draw the pin out.

Having thus described my invention what I claim is:

A cotter pin puller consisting of a pair 70 of members, one of said members comprising a handle portion and an enlarged jaw extending upwardly and forwardly from said handle portion, said jaw comprising two spaced portions, the forward ends of 75 said spaced portions being bent downward to form bearing surfaces and said bearing surfaces having serrations thereon, the other of said members comprising a handle portion ending in a tapered pin engaging portion pivoted between said jaw portions, said pin engaging portion being curved upwardly and terminating in a point, said tapering pin engaging portion being so curved as to extend between and above said spaced portions of said jaw and of such thickness as to leave clearance for a cotterpin head between its sides and the inner sides of said spaced 80 85 jaw portions.

In testimony whereof I hereto affix my 90 signature in the presence of a witness.

JEFFERSON B. HAYDEN.

Witness:

BOYD CORMLISON.
